By his Attorney,
Nelson M. Howard

UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF LASTING SHOES.

Original application filed January 21, 1922, Serial No. 530,968. Divided and this application filed December 8, 1926. Serial No. 153,401.

- This invention relates to the lasting of boots and shoes, the present application being a division of my copending application Serial No. 530,968, filed on January 21, 1922.
- 5 The invention is herein illustrated in its application to the lasting of the shank portion of tennis shoes or sneakers, in the manufacture of which it is customary to fasten the margin of the upper in lasted relation to the insole by adhesion through the use of cement. It will be evident, however, that the invention is not limited to shank lasting nor to the manufacture of shoes of the particular type illustrated.
- 10 It is an object of the invention to provide a method by the use of which portions of shoes of the above-mentioned or other types may be lasted more quickly, easily and satisfactorily than heretofore. In the lasting of shoes in which the margin of the upper is fastened to the insole by the use of cement, it is necessary that the upper be drawn tightly over the last before the margin of the upper is brought into contact with the bottom face of the insole and that the margin of the upper then be pressed against said face to cause it to adhere thereto. In accordance with the method of this invention, in its illustrated application to the lasting of the shank portions of shoes, the side of a shoe is presented in engagement with a lasting tool, preferably a driven tool as herein shown, and the shoe is turned or rocked about a longitudinal axis to render the tool progressively effective to draw the upper tightly into conformity to the contour of the last and then to bend it about the edge of the shoe bottom and to press its margin upon the bottom face of the insole. In the lasting of shoes in which the margin of the upper is fastened to the insole by cement, the upper is thus drawn tightly over the last while its margin is out of contact with the bottom face of the insole, and by the turning of the shoe while held in engagement with the tool the margin of the upper is then bent inwardly into substantially parallel relation to the bottom face of the insole and caused to adhere to said face without any relaxation of the lasting tension. In a further aspect of the method, it is contemplated that pressure will be applied to the insole, preferably near

that portion of its marginal edge where the upper is bent inwardly over it, to insure that the insole will be positioned and maintained 55 in close conformity to the contour of the bottom of the last until the upper has been cemented to it.

The novel method will now be more particularly described by reference to the accompanying drawings and thereafter set forth in the claims. The drawings conveniently illustrate the practice of the method by the aid of a machine constructed as described in the above-mentioned copending application, although it is to be understood that the invention is not dependent upon the use of any particular machine or apparatus.

In the drawings, 70
Fig. 1 is a perspective view of the head portion of the machine shown in the copending application;

Figs. 2 and 3 are vertical sections through the shoe-support and the shank portion of a shoe on said support, illustrating different positions of the support and the shoe in relation to the lasting tool in the course of the lasting operation; and

Fig. 4 shows the shoe and the lasting tool so in substantially the same relation as in Fig. 2, but as viewed from a point underneath the shoe.

As described in the copending application, the machine herein shown as adapted for use 85 in the practice of the method comprises a supporting standard 2 upon which is rotatably mounted a shaft 4 arranged to be driven by a belt on a pulley 6 and carrying at one end a lasting roll 8. For the illustrated purpose of shank lasting, this roll is of such length as to extend substantially from the ball line of the shoe rearwardly to the heel seat, so as to last at one operation the entire shank portion of the shoe at either side, 95 the periphery of the roll being convex in the direction of its axis to conform approximately to the concavity of the shank of the shoe. To render the roll effective to tighten the upper over the last by frictional engagement therewith, it is provided on its periphery with a band 10 of rubber having therein corrugations 12 extending lengthwise of the roll. In operation the roll 8 is

driven continuously in the direction of the arrow *a*. To assist in presenting the shoe to the lasting roll, the machine is provided with a shoe support comprising a pair of arms 14 which are fast on a rock shaft 16 mounted in a bearing in a vertically adjustable bracket 18. Mounted on pivots 20 at the upper ends of the arms 14 is a stirrup-shaped shoe rest member or holder 22. The holder 22 has adjustably mounted thereon a plate 24 provided with an upwardly bent end having a convex edge face 26 for engagement with the insole of the shoe near its edge, as illustrated in Fig. 2. Also adjustably supported on the holder 22 is a shoe rest member 28 arranged for engagement with the shoe on the opposite side from the roll. The shoe support, when not in use, is maintained in a forwardly tipped position by means of a spring 30, this position being determined by a stop screw 32 which is carried by a depending lug on one of the supporting arms 14 and is arranged to engage the bracket 18. To assist in swinging the shoe support toward the lasting tool, one of the arms 14 is provided with a member 34 adapted to be engaged by the operator's hip.

In carrying out the method of the invention to last, for example, the shank portion of a rubber-soled shoe which has been previously lasted at the forepart and the heel end, the shoe is presented in engagement with the positioning members 24 and 28, with the convex edge 26 of the plate 24 engaging the shank portion of the insole in a location near that side of the shoe that is toward the lasting roll, but preferably farther from the edge of the insole than the margin of the upper is to extend when it is wiped inwardly. It will be understood that the holder 22 hangs substantially vertical when the shoe is thus presented to it, and after the shoe has been positioned upon the members 24 and 28, the holder 22 is tipped by the operator so that when the shoe support is swung rearwardly the side of the shoe will be presented in engagement with the lasting roll at a distance from the bottom edge of the upper, for example, as illustrated in Fig. 2. In thus presenting the shoe the operator will preferably engage it with both hands at its opposite ends and will effect the tipping or turning of the holder 22 through the shoe. As the roll engages the side of the shoe it acts frictionally to draw and press the upper into conformity to the contour of the last. While holding the shoe in engagement with the roll, the operator turns the shoe and its holder 22 in the direction of the arrow *b* to a position such as illustrated, for example, in Fig. 3, thus effecting a transfer of the area of effective engagement of the roll with the upper toward the edge of the upper and rendering the roll effective, as it

draws the upper over the last and holds it tightly in conformity to the contour of the last, to bend and wipe its margin inwardly into substantially parallel relation to the bottom face of the insole and to press it upon said face, so that cement previously applied to the upper or to the insole becomes effective to fasten the upper in lasted position. The axis of turning movement of the shoe, represented by a line connecting the pivots 20, will preferably be substantially parallel to the axis of the roll 8 and will intersect the shoe substantially or approximately at the center of curvature, in a plane perpendicular to the shoe bottom, of that portion of the shoe upon which the roll acts in the lasting operation, so that the shoe may be turned as illustrated without any substantial bodily displacement of it, the operator simply maintaining pressure on the member 34 to hold the support as a whole in shoe-presenting position. By reason of the lengthwise convexity of the peripheral surface of the roll and the yielding character of the rubber band 10, the roll conforms substantially to the lengthwise curvature of the shank of the shoe and is effective to work the upper tightly into lasted position at all portions of the shank.

After having performed the lasting operation in the manner described at one side of the shoe, the operator permits the shoe support to swing forwardly, and having reversed the shoe end for end presents its other side to the lasting tool to complete the lasting at that side of the shoe. The shoe is then completely lasted and is ready for the sole-laying operation.

As the shoe is turned to render the lasting roll effective to lay the margin of the upper inwardly over the insole, the sole rest member 24 holds the marginal portion of the insole from being displaced by the inwardly directed pressure of the roll and also holds the insole closely against the bottom of the last in the inward curve at the shank until the margin of the upper has been cemented to it, thus preventing the margin of the upper from adhering to the insole prematurely with the margin of the insole unduly separated from the bottom of the last. This insures that the insole as well as the upper will be properly conformed to the contour of the last.

Having described the novel method and set forth fully how it may be practised, what I claim as new and desire to secure by Letters Patent of the United States is:

1. That improvement in methods of lasting shoes in which the margin of the upper is fastened to the insole by adhesion, which consists in presenting a shoe in engagement with a driven lasting tool at a distance from the bottom edge of the upper and in such position that the movement of the upper-

engaging face of the tool is along the surface of the upper in a direction transverse to the edge of the shoe bottom, and by turning or rocking the shoe transferring the area of effective engagement of the tool with the upper toward the bottom edge of the upper to bend the margin of the upper inwardly and press it into adhering relation to the bottom face of the insole.

10 2. That improvement in methods of lasting shoes which consists in presenting a shoe in engagement with a driven frictional lasting tool in such position that the tool by its movement wipes the upper heightwise of the shoe, and while maintaining the shoe in engagement with the tool turning or rocking the shoe until the tool wipes the margin of the upper into substantially parallel relation to the bottom face of the insole.

15 3. That improvement in methods of lasting shoes in which the margin of the upper is fastened to the insole by adhesion, which consists in presenting the side of a shoe in engagement with a driven lasting roll rotating about an axis extending lengthwise of the shoe, and turning or rocking the shoe in a plane transverse to its length while maintaining it in engagement with said roll to tighten the upper over the last and to bend its margin inwardly into adhering relation to the bottom face of the insole.

20 4. That improvement in methods of lasting shoes in which the margin of the upper at the shank is fastened to the insole by adhesion, which consists in presenting the side of a shoe in engagement with a frictional lasting tool constructed to act upon substantially the entire length of the shank at one operation, and by turning or rocking the shoe laterally transferring the area of effective engagement of the tool with the upper toward the bottom edge of the upper to bend the margin of the upper inwardly and press it into adhering relation to the bottom face of the insole.

25 5. That improvement in methods of last-

ing shoes in which the margin of the upper is fastened to the insole by adhesion, which consists in presenting a shoe in engagement with a lasting tool at a distance from the bottom edge of the upper, turning or rocking the shoe to transfer the area of effective engagement of the tool with the upper toward the bottom edge of the upper and thereby render the tool effective to bend the margin of the upper inwardly into substantially parallel relation to the bottom face of the insole and to press it into adhering relation to said face, and while thus turning or rocking the shoe engaging the insole to hold it closely against the bottom of the last as the margin of the upper is bent inwardly over it.

30 6. That improvement in methods of lasting shoes which consists in applying pressure to the insole of a shoe near its side edge to hold it in place on the bottom of the last, and while thus holding the insole presenting the side of the shoe in engagement with a driven frictional lasting tool and turning or rocking the shoe laterally in engagement with said tool to wipe the margin of the upper inwardly into substantially parallel relation to the bottom face of the insole.

35 7. That improvement in methods of lasting shoes in which the margin of the upper at the shank is fastened to the insole by adhesion, which consists in presenting the side of a shoe at the shank in engagement with a driven frictional lasting tool, turning the shoe laterally to render the tool effective to wipe the margin of the upper into adhering relation to the bottom face of the insole, and while thus turning the shoe pressing the insole into the shank curvature of the last bottom to prevent premature adherence of the upper to the margin of the insole.

40 In testimony whereof I have signed my name to this specification.

BERNHARDT JORGENSEN.
